Primary Examiner — Eric Goodman*Assistant Examiner* — Christian P McLean(74) *Attorney, Agent, or Firm* — Banner & Witcoff, Ltd.**CLAIM**

The ornamental design for a display screen with transitional graphical user interface, as shown and described.

DESCRIPTION

FIG. 1 is the first image in a sequence for a display screen with transitional graphical user interface shown on a device showing our new design;

FIG. 2 is the second image in the sequence thereof;

FIG. 3 is a rear view of the device thereof;

FIG. 4 is a left side view of the device thereof;

FIG. 5 is a right side view of the device thereof;

FIG. 6 is a top view of the device thereof; and,

FIG. 7 is a bottom view of the device thereof.

The broken line showing of the remainder of the user interface, the remainder of the display screen, and the device is for environmental purposes only and forms no part of the claimed design. The appearance of the image transitions sequentially between the images shown in FIGS. 1 through 2. The process or period in which one image transitions to the other forms no part of the claimed design.
